UNITED STATES PATENT OFFICE.

FRANK A. McNALLY, OF DALLAS, TEXAS, ASSIGNOR OF ONE-THIRD TO H. M. GARDNER
AND ONE-THIRD TO H. H. GARDNER, BOTH OF DALLAS, TEXAS.

STALK-CUTTER.

1,201,065.

Specification of Letters Patent. Patented Oct. 10, 1916.

Application filed January 5, 1915. Serial No. 563.

To all whom it may concern:

Be it known that I, FRANK A. McNALLY, a citizen of the United States, residing at Dallas, in the county of Dallas and State 5 of Texas, have invented certain new and useful Improvements in Stalk-Cutters, of which the following is a specification.

My invention has relation to that class or 10 type of cutting machines known as stalk cutters in which the wheels of the vehicle carrying the cutters furnish, when the vehicle is driven, the motive power for revolving the cutter shafts and cutters. In such 15 connection the present invention relates more particularly to the construction and arrangement of the cutting mechanism, the power transmitting mechanism connecting the wheels of the vehicle with the cutter shafts, and the cutter knives and means for 20 securing the same to the cutter shafts.

One of the main objects of my present invention is to provide a series of depending 25 cutter shafts, operated by the wheels of the vehicle, each of said shafts carrying a plurality of cutter knives arranged and turning 30 in a plurality of horizontal planes to cut the stalk into a plurality of pieces, the knives of successive planes projecting at varying angles with respect to each other.

A second object of my invention is to provide in a corn stalk cutter a series of depending cutter shafts and cutter knives in a plurality of planes and varying angles 35 carried by each of said shafts, the cutter shafts and cutters being so arranged that the cutters on one shaft revolve in planes staggered with relation to the planes of revolution of the cutters on adjacent cutter 40 shafts.

Further objects of my invention are to provide a cutting blade of improved construction and to provide an improved means for fastening or securing said blade to its 45 shaft.

The nature and scope of my invention will be more fully explained in the following specification and illustrated in the accompanying drawings, wherein:—

50 Figure 1 is a top or plan view of a stalk cutter embodying main features of my invention—the shield inclosing the working parts being broken away. Fig. 2 is a rear

elevational view of the same, the shield being broken away to more clearly disclose 55 the cutter shafts and operating mechanism therefor. Fig. 3 is an end elevational view of the machine. Figs. 4 and 5 are enlarged views respectively in elevation and in plan of the knife, showing the same connected 60 with the cutter shaft, and Fig. 6 is a side elevational view enlarged of the clamp for locking the knife to the cutter shaft.

Referring to the drawings 1—1 represent the traction wheels of the stalk cutter and 65 2—2 represent the shafts or axles to which said wheels are secured. Each axle 2 has an inner bearing or support 3 in the lower end of a bracket or arm 4 and the two brackets 4 are connected firmly together at their upper 70 ends by the cross-piece 5. Upon a platform 5^a projecting forwardly from said cross-piece 5 is mounted in any suitable manner, the seat 6 for the driver of the vehicle.

Above the cross-piece 5 and below the seat 75 6 is arranged the power shaft 7 to which are splined or otherwise slidably secured, at suitable distances apart, the miter gears 8. The power shaft 7 turns in bearings 9 formed in bracket arms 10 projecting upward from and supported rigidly by the cross-piece 5. This shaft 7 is arranged parallel with and preferably in the same vertical plane as the axles 2 and cross-piece 5. The miter gears 8 may be shifted back 80 and forth upon the shaft 7 to which they are feathered or splined by means of the clutch collars 11 engaged by the forked end of the clutch arms 12.

A rod 13, sliding in bearings 14, carried 90 by cross-piece 5, is adapted to be shifted to right or left as occasion demands by means of the bell crank lever 15 operated by the hand lever 16 by the operator in seat 6. The bell crank lever 15 has its fulcrum in platform 5^a and the handle 16 with its ratchet control 17 are also supported upon said platform as clearly shown in Fig. 3.

Below the cross-piece 5 and suitably supported by braces 18 extending from the 100 axle brackets 4 is a crossrod 19 forming one of the bearings for a series of vertically disposed cutter shafts 20. These shafts 20 traverse the cross piece 5 and have bearings 21 arranged in the upper face of said cross 105 piece 5. The bearings 21 on cross piece 5

and corresponding bearings 22 on cross rod 19 are preferably ball bearings of any well known type. Above the upper bearings 21 and upon the shafts 20 are fixed the miter 5 gears 23, so arranged that when the positively driven miter gears 8 of power shaft 7 are shifted in one direction, say from right to left in Fig. 1, the said positively driven gears 8 will mesh with gears 23 to 10 positively drive the cutter shafts 20. A reverse movement of gears 8 on shaft 7 will free said gears from the cutter shaft gears 23 and said shafts 20 will cease to revolve or rotate. Each cutter shaft 20 in machine 15 is provided between bearings 21 and 22, with a polygonal sleeve 24 which is preferably hexagonal in cross section and which is secured to the shaft 20 by bolts 25 or by any suitable means. The cutter shafts below 20 the lower bearing 22 are each provided with a sleeve 26 similar to sleeve 24 and secured to the shaft 20 by bolts 25. To the polygonal sleeves 24 and 26 are secured the cutter knives 27, the construction and arrangement of which together with the manner of and means for fastening the same to the shafts 20 form important features of the present invention.

Referring now to Figs. 4, 5 and 6 wherein 30 the construction and arrangement of the knives and the means and manner of securing the same to the cutter shaft are illustrated in detail, it will be observed that each knife 27 is provided with a flat shank 28 and a curved blade 29 formed by twisting the knife blank as at 29^a until the edge of the knife blade 29 projects in a plan at right angles to the face of the shank 28. The knife blade 29 is curved to form virtually a 35 sickle or a scythe blade. A yoke-shaped clamp 30 has its two wings 31 vertically slotted as at 32 to receive and interlock with the polygonal sleeve 24 or 26. Where said sleeves are hexagonal as illustrated in the drawings, the slots or recesses 32 in wings 40 31 are hexagonal. If the sleeves are formed with more or less sides, then the slots 32 correspond. The yoke-clamp 30 has a transverse opening 33 extending longitudinally 45 beyond the sleeves in both directions. When the clamp 30 is slid in on sleeve 24 or 26 there is formed adjacent to the body of said clamp 30 a transverse slot into which the shank 28 of the knife may be inserted to rest more or 50 less firmly upon a flat face of the sleeve 24 or 26 inclosed by the winged members of the clamp. A set screw 34 serves to press the shank 28 of the knife firmly to the 55 sleeve and thereby not only locks said knife 60 to the cutter shaft but also locks the clamp against vertical movement upon the polygonal sleeve.

Where as in the construction shown in the drawings, each cutter shaft is hexagonal it follows that each shaft 20 is provided with 6

knives. Each knife is secured to and projects from a different side of the hexagon and each knife is arranged on its shaft some distance from the next succeeding or preceding knife in series.

In the drawings I have shown a machine provided with four cutter shafts since the machine is designed to cut two rows of stalks. For each row of stalks a pair of cutter shafts is necessary. Thus in Fig. 2 75 for instance the first and second cutter shafts (from right to left) coöperate to cut one row of stalks whereas the third and fourth cutter shafts coöperate to cut the second row of stalks. Considering but one 80 pair of cutter shafts it will be observed that the first or top knife of the first cutter shaft coöperates with the first or top knife of the second shaft to cut through the stalk at one 85 point above the ground and that succeeding knives in series on the first shaft likewise coöperate with corresponding knives in series of the second shaft to cut said stalks at other points above the ground, in other words the stalk, where six knives in each 90 shaft are used, will be cut at six different points. The knives of the second shaft revolve in planes slightly above the planes of rotation of coöoperating knives of the first shaft. In other words when the stalk is 95 caught between coöoperating knives, it is cut by a substantially scissorlike operation.

It will be understood that inasmuch as each shaft 20 rotates with considerable velocity all six cuts upon the stalk are practically simultaneous and hence no crushing of the stalks can take place. In case of the accidental breaking of a knife it is a simple matter to unloosen set screw 34 withdraw the damaged knife and replace with a new 105 knife.

Power is transmitted from axle 2 to shaft 7 by means of an ordinary chain 35 and sprocket 36, mechanism well known in the art.

Having thus described the nature and object of my invention what I claim as new, is:—

1. In a machine of the character described a pair of depending cutter shafts 115 and means for rotating the same, a series of single cutter blades projecting from each shaft at varying angles and each turning in a plane separate from the plane in which the other blades rotate, the blades in series of one shaft coöperating with corresponding blades of the other shaft to cut the stalk by a scissorlike operation.

2. In a machine of the character described, a series of depending cutter shafts 125 arranged to coöperate in pairs, each cutter shaft being provided with a series of single cutter blades, means for securing each blade to the shaft at a point above or below the succeeding or preceding blade in series,

said means being adjustable on the shaft to permit the blade to project at varying angles from said shaft.

3. In a machine of the character described, a cutter shaft, a sleeve polygonal in cross section secured to said shaft, a yoke shaped clamp having wings traversed by and interlocking with said sleeve, and a cutter blade having a shank arranged to be

secured to a face of said sleeve by said clamp.

In testimony whereof I have signed my name to this specification in the presence of two subscribing witnesses.

FRANK A. McNALLY.
